UNITED STATES PATENT OFFICE.

WILLIAM G. EATON, OF BOSTON, MASSACHUSETTS, ASSIGNOR TO UNITED SHOE MACHINERY COMPANY, OF PATERSON, NEW JERSEY, A CORPORATION OF NEW JERSEY.

CEMENTING MACHINE.

1,080,959.

Specification of Letters Patent.

Patented Dec. 9, 1913.

Application filed September 19, 1908. Serial No. 453,817.

To all whom it may concern:

Be it known that I, WILLIAM G. EATON, a citizen of the United States, residing at Boston, in the county of Suffolk and Commonwealth of Massachusetts, have invented certain Improvements in Cementing Machines, of which the following description, in connection with the accompanying drawings, is a specification, like reference characters on the drawings indicating like parts in the several figures.

This invention relates to machines for applying cement or other coating material, which will be herein generally referred to as cement, to stock.

For the purpose of explanation the invention is herein shown as embodied in a machine adapted for applying a thin coating of cement to one side of sheet stock such as pieces of lining or doubling material used in the manufacture of boots and shoes. Many of the features of the invention are however adapted for use in other types of machines and no limitation is to be understood beyond those explicitly stated in the claims. The lining or doubling material referred to usually has a nap or furry surface on the side to which the cement is to be applied and it is desirable to coat this napped surface with just sufficient cement to cause it to adhere to the leather. The nap then forms a flexible and yielding connection between the leather and the body of the lining or doubling material which latter is not itself wet with the cement and consequently is not stiffened by the cement. For this work it is important that an even or uniform light coating of cement be applied to the stock which shall connect the nap to the leather throughout its entire area but not soak into the body of the stock at any point. It is also desirable that thin cement be used. An important feature of the present invention consists in the construction and arrangement of the cement supplying and applying means whereby a thin coating of uniform thickness is applied to the stock.

A novel characteristic of this invention is found in the arrangement for driving the cement supplying roll and the cement applying roll one from the other without the use of gears or belting and without interfering with the suitable transferring of the cement from the former to the latter roll. To the end one of the rolls, herein shown as t

supplying roll is formed or provided with a radially extended rim at each end for engaging the periphery of the other roll and driving it. This rim projects just far enough beyond the body portion or cement carrying surface of the roll to permit a suitably thin coating of cement to be carried between the adjacent surfaces of the two rolls. This arrangement has the advantage that a definite body of cement is transferred from the supplying roll to the applying roll. In the use of thin cement this cannot be satisfactorily done with rolls that are driven with their cement carrying faces in contact. The present arrangement has the advantage in construction over rolls independently driven in opposite directions as is common that additional mechanism, as gears or belting, is dispensed with, and the more important advantages in operation that a definite quantity or coating of cement is transferred to the applying roll, the cement is evenly distributed over the roll, and any thick portions of cement which may exist are rolled or flattened out.

An adjustable scraper or shedder is preferably employed for removing surplus cement from the applying roll. In the use of machines as heretofore constructed for cementing linings and doublers a serious difficulty has been experienced because particles of lint and portions of other foreign matter from the cement or from other sources caught between the shedder and the surface of the applying roll and wiped a streak or band on the roll dry of cement or prevented the adjacent portion of the roll from carrying past the shedder its appropriate coating of the thin cement which is used. The adherence of other portions of foreign matter to the one first caught between the shedder and the roll soon widens the bar streak on the roll so that the stock does not receive a satisfactory coating. It is customary in the use of such machines for the operator to run a stick or a file under the shedder, between it and the roll to clear away these obstructions when the work becomes too unsatisfactory, but in practice this is largely neglected because it delays the operator and it is an awkward operation.

It is one of the objects of this invention to overcome this difficulty and insure a clean shedder and an evenly coated applying roll. To this end a very important feature of

2
this invention consists in making provision for automatically cleaning the shedder. This is effected as herein shown by intermittently varying the relation between the shedder and the adjacent portion of the periphery of the roll between which obstructions are liable to catch. This can be effectively done in many ways and I have herein shown arrangements for varying intermittently the 5 distance between the shedder and the periphery of the roll. By this means the obstructions are wiped from the shedder or squeezed from between the shedder and the roll to dislodge them. In the preferred 10 form the roll has a projection, herein shown as a bar extending lengthwise of the roll and embedded in its peripheral face, which intermittently wipes across the shedder. Either the shedder or the roller projection 15 20 may advantageously be arranged to yield, and preferably the shedder will be slidingly mounted and held toward the roll by spring pressure.

A further feature of this invention consists in heating the cement by which treatment it is rendered more fluid so that a thinner coating can be applied to the stock and at the same time its sticking power is increased. To this end the cement holder 25 30 is provided with heating means which may conveniently be an electric heater whereby the cement is maintained in a heated condition without danger of producing a flame, and the cement supplying and applying rolls 35 40 are warmed by the cement so that the latter is applied to the stock in a heated condition. It is the practice in using the machine for the operator to take the piece of stock from the applying roll and apply it directly to the leather to which it is to be attached so that 45 it is caused to adhere while it is in a heated or warmed condition. It is found that better results can be obtained by heating the cement as well as a saving in cement effected because the smaller quantity of heated cement required stiffens the stock less than the quantity required when the cement is applied at a normal temperature.

These and other features of the invention, 50 including certain details of construction and combinations of parts will be explained in connection with the following description of a machine and will be pointed out more definitely in the claims.

55 Figure 1 is a front view of the machine. Fig. 2 is a vertical section through the lower or cement supplying roll. Fig. 3 is a left hand view of the machine as shown in Fig. 1. Fig. 4 is a vertical section on the line 4-4 of Fig. 3. Fig. 5 shows a modification on a similar line. Fig. 6 shows a further modification.

The machine is adapted to project upwardly through the surface of a bench or 60 65 table indicated at 1 and is adjustably sup-

ported on a post 2 by a screw 3. The head or frame 4 of the machine has a laterally projecting bracket 5 having guideways to receive the runners or slides 6 of a cement receptacle 8 which can be removed for filling or cleaning by pulling it forwardly. An electric heater shown as a cylindrical member 10 is arranged to fit in a recess formed partially in the runners of the cement receptacle and partially in the bracket 5 whereby it locks the receptacle in a predetermined position in the machine. The main object of this heater is, of course, to heat the cement and obviously also to heat the cement rolls.

80 The cement receptacle is provided in its upper end faces with notches to receive the bearing blocks 12 of a cement roll shaft 14 upon which turns the cement supplying roll or that roll which dips into the receptacle 85 and lifts the cement into position to be delivered to the applying roll. The bearing blocks may be turned by the handle 16 to shift the cement supplying roll from and toward the coöperating roll. A box or cage 90 95 20 is fitted into the cement receptacle and is formed and arranged to receive that portion of the roll which dips into the cement. One or more faces of this box are made of wire screen or other suitable material to strain the cement and assist in preventing particles of foreign matter from reaching the roll.

100 The preferred construction of the cement supplying roll is shown in Fig. 2, to consist of end members 25 adapted to turn freely upon the shaft 14 and supporting a cylindrical member 26. Preferably the peripheral edges of the end blocks 25 project radially beyond the periphery surface of the cylindrical member 26 which latter surface forms the cement carrying face of the roll. The projecting end blocks are adapted to engage and be held yieldingly by the spring plungers 15, before mentioned, against the periphery of the cement applying roll. These 105 projecting end blocks thus constitute a driving connection between the two rolls and they therefore serve to hold the cement carrying surface of the supplying roll spaced. 110 a predetermined distance away from the adjacent surface of the other roll to which cement is to be delivered. This arrangement insures the delivery of sufficient cement for the purposes for which this machine is intended even though the cement is of a thin 115 character and is rendered even more fluid by heating it as contemplated by this invention.

120 The cement applying roll referred to is preferably substantially larger than the supplying roll as shown. An object of this arrangement is to permit the supplying roll to be located in convenient position below the bench or table while the applying roll projects above the table. The shaft of the 125 130

applying roll 30 is mounted in suitable bearings in the frame 4 and is driven by a worm and gear connection with a pulley shaft 32, the gear being loose on the shaft and adapted to be connected by a clutch device 34 operated by a lever 35 as shown above in Fig. 3. The frame has a bracket 36 projecting to the left as shown in Fig. 1 and supporting a scraper or shedder 40 adapted to remove superfluous cement from the applying roll as the cement is carried upwardly into position to be used. The shedder is located above the supplying roll and its lower edge is corrugated or notched to facilitate the dripping of the cement back upon the supplying roll. The shedder is adjustably mounted on the bracket 36 as shown in Figs. 1 and 4, being carried by screws 42 turning in a block 44, secured to the bracket, and fastened in adjusted position by lock nuts. The screw extends through an upstanding lug on the shedder and is headed at its front end while a spring 45 is interposed between said lug and the block 44 so that the shedder can yield backwardly or away from the roll but is normally held yieldingly toward the roll in a position determined by the adjustment of the screw 42. The shedder and a portion of the periphery of the applying roll are relatively formed to cause the shedder to be automatically cleaned or cleared from obstructions such as lint and particles of other foreign matter which may gather between the shedder and the roll. As shown in Fig. 4, the roll carries a projecting member 46, extending lengthwise thereof across its periphery and adapted to engage the shedder and as it wipes upwardly across the edge of the shedder to force the latter backwardly from the roll and clear it from obstructions. The yielding mounting for the shedder permits the shedder to move from and toward the roll as this projection passes it. In Fig. 5, the shedder is unyieldingly mounted and the roll carries a projection 48 of yielding material such as felt. In Fig. 6, the periphery of the roll is provided with a depression or recess 50 into which obstructions may dislodge as the roll turns in the movement of the recessed portion past the shedder.

In the use of the machine, the operator may conveniently stand in front of the machine with a pile of pieces of stock to be cemented on the table at the left of the machine and a pile of pieces to which the cemented portions are to be attached at the right of the machine. As the rolls turn the operator takes up a piece of doubling material and lays it upon the roll, preferably guiding it to the roll over the inclined shield 52 which covers the shedder. The operator presses the stock lightly upon the roll permitting the stock to travel forward at the same rate at which the roll turns and then lifting or stripping the stock from the roll.

As the stock is removed the cement adheres to the nap and thus causes the nap to stand up from the body of the stock. The cement-coated portion of stock is then laid down upon the portion to which it is to be attached and the double portions as they accumulate are piled one upon the other so that the cement is permitted to set while the two plys of the double stock rest lightly upon one another. This is preferable to pressing the double portions close together for it permits the end portions of the nap to stick to the leather without liability of the cement being forced into the body of the cloth. The nap thus forms a yielding and flexible connection between the leather and the cloth which gives the double portion of stock desirable characteristics resembling those of much thicker and more expensive leather. When such stock is used in a shoe the lining covers and conceals the doubling material.

Having explained the nature of this invention and described a preferred construction embodying the same, I claim as new and desire to secure by Letters Patent of the United States:—

1. A machine for applying liquid cement, having in combination, a cement applying roll, a shedder therefor arranged in approximate contact with the roll to limit at all times to a thin film the cement carried by the roll and means for driving the roll, said machine having provision for intermittently varying the relation between the shedder and the adjacent portion of the periphery of the roll to dislodge obstructions. 95

2. A machine of the class described, having in combination, a cement applying roll, a shedder therefor and means for driving the roll, said machine having provision for automatically varying at intervals the space between the shedder and the adjacent portion of the periphery of the roll. 105

3. A machine of the class described, having in combination, a cement receptacle, a cement supplying roll, and a cement applying roll, one of said rolls having a cement carrying face and an annular radially extended portion adapted to engage and have driving connection with the other roll. 110

4. A machine of the class described, having in combination, a cement receptacle, a cement supplying roll, and a cement applying roll, one of said rolls having a cement carrying face and a raised driving face at each end adapted to form a driving connection with the other roll and to hold the cement carrying face of the two rolls separated a predetermined distance. 120

5. A machine of the class described, having in combination, a cement applying roll, means for driving it, a cement supplying roll, a cement receptacle, means for yieldingly holding the supplying roll toward the 130

applying roll, and a rim or raised surface on each end of the supplying roll adapted to hold the cement carrying faces of the two rolls spaced apart and to form a driving connection between the two rolls.

6. A cement applying machine having, in combination, a cement applying roll, a second roll arranged to supply cement at all times to the first roll, said second roll having a raised face at each end, a cement receptacle in which said second roll is rotatably mounted, means for yieldingly pressing said second roll toward said applying roll, and means for adjusting said second roll toward and from said applying roll.

7. A machine of the class described, having in combination, a cement carrying roll, a cement receptacle, a support therefor from which the receptacle is removable, and an

electric heater constructed and arranged to interlock with the support and the receptacle to secure the latter in operative relation to the roll and to heat the cement therein.

8. A machine of the class described having, in combination, a cement applying roll, means for rotating said roll, a clearer projecting at all times from the periphery of the roll and a shedder having an extended portion projecting into the path of said clearer.

In testimony whereof I have signed my name to this specification in the presence of two subscribing witnesses.

WILLIAM G. EATON.

Corrections in Letters Patent No. 1,080,959.

It is hereby certified that in Letters Patent No. 1,080,959, granted December 9, 1913, upon the application of William G. Eaton, of Boston, Massachusetts, for an improvement in "Cementing-Machines," errors appear in the printed specification requiring correction as follows: Page 1, line 98, for the word "bar" read *bare*; page 2, line 105, for the word "periphery" read *peripheral*; page 3, line 103, strike out the words "of the class described" and insert the words *for applying liquid cement*; and that the said Letters Patent should be read with these corrections therein that the same may conform to the record of the case in the Patent Office.

Signed and sealed this 16th day of June, A. D., 1914.

[SEAL.]

J. T. NEWTON,

Acting Commissioner of Patents.

applying roll, and a rim or raised surface on each end of the supplying roll adapted to hold the cement carrying faces of the two rolls spaced apart and to form a driving connection between the two rolls.

6. A cement applying machine having, in combination, a cement applying roll, a second roll arranged to supply cement at all times to the first roll, said second roll having a raised face at each end, a cement receptacle in which said second roll is rotatably mounted, means for yieldingly pressing said second roll toward said applying roll, and means for adjusting said second roll toward and from said applying roll.

7. A machine of the class described, having in combination, a cement carrying roll, a cement receptacle, a support therefor from which the receptacle is removable, and an

electric heater constructed and arranged to interlock with the support and the receptacle to secure the latter in operative relation to the roll and to heat the cement therein.

8. A machine of the class described having, in combination, a cement applying roll, means for rotating said roll, a clearer projecting at all times from the periphery of the roll and a shedder having an extended portion projecting into the path of said clearer.

In testimony whereof I have signed my name to this specification in the presence of two subscribing witnesses.
